LEO C. SMITH, OF MINNEAPOLIS, MINNESOTA, ASSIGNOR TO SMITH SYSTEM HEATING COMPANY, OF MINNEAPOLIS, MINNESOTA, A CORPORATION OF MINNESOTA

LAVATORY AND BUBBLING FOUNTAIN UNIT

Application filed July 25, 1931. Serial No. 553,039.

My present invention provides an improved combined lavatory and bubbling fountain designed, constructed and adapted to be applied as a self-contained unit and especially serviceable for use in rural school houses and similar places where city water supply is not available.

Generally stated, the invention consists of the novel devices, combinations of devices and arrangement of parts hereinafter described and defined in the claims.

The invention is illustrated in the accompanying drawings wherein like characters indicate like parts throughout the several views.

15 Referring to the drawings:

Fig. 1 is a view chiefly in front elevation, but with some parts broken away and some parts sectioned showing the complete unit;

Fig. 2 is a perspective showing the shelf-like supporting base for the elements of the unit;

Fig. 3 is a fragmentary section taken on the line 3—3 of Fig. 2; and

Fig. 4 is a fragmentary section taken on the line 4—4 of Fig. 2.

The shelf-like supporting bracket comprises a horizontal marginal frame 5 preferably an angle iron, rigidly secured to and arranged to be supported by vertically depending wall angles 6 and oblique brace angles 7, which parts are rigidly connected preferably by rivets. Lag screws 8 applied through flanges of the angles 6 and into the studding 9 of the building serve to rigidly 35 secure the bracket in the desired position.

The water tank 10, which preferably is an insulated tank, is mounted on the supporting bracket, the latter being preferably provided with a rigidly secured flanged disc or shallow 40 pan 11 into which the water tank is set. Preferably, the pan 11 is secured to the frame of the supporting bracket by nut-equipped bolts 12, so that the said pan can be secured either to the right or to the left-hand side of said 45 supporting bracket. The lavatory bowl 13 will be, of course, secured to the other side of the bracket, that is, if the tank is applied at the right-hand side, the lavatory bowl will be applied at the left, and conversely. A main 50 drain pipe 14 extends downward from the

bottom of the lavatory bowl 13 and in this drain pipe is interposed a water trap 15 of the self-sealing type preferably provided with a drain valve 16. Extended downward from the bottom of the tank 10 is a discharge 55 pipe 17 in which is interposed a normally closed valve 18. The bowl 13 is provided with a suitable discharge faucet 19 that is connected by a small pipe 20 to the discharge pipe 17 at a point above the valve 18. The 60 lower end of the discharge pipe 17 is connected by a small drain pipe 21 to the main drain pipe 14, at a point above the trap 15.

Supported from and closely adjacent to the tank 10 is a bubbling fountain 22 that 65 receives drinking water from the tank 10 through a pipe 23 that is provided with a normally closed valve or faucet 24 of any suitable type that is adapted to be readily opened by a person desiring to drink from the fountain.

The bubbling fountain 22 is provided with a discharge or drain pipe 25 that is connected to the pipe 17 or 21 at a point below the normally closed valve 18. As shown, pipe 70 75 25 is passed through a perforated lug 26 that is detachably secured to the frame 5 preferably by a nut-equipped bolt 27 arranged to be applied through a hole at the right, as shown in the drawing, or to be applied through a hole 28 at the left, as shown by dotted lines in Fig. 2.

From the foregoing, it is evident that all of the parts of the unit may be completed at the factory and quickly assembled at the 85 place where they are to be used with the tank and lavatory bowl either in right and left or left and right arrangement according to which will be the best arrangement for the particular place of installation. Also it is 90 evident that the relative arrangement of the valves and pipes and traps and the like is important.

Normally, valve 18 will, as already indicated, be closed and valve 24 will be closed except when the bubbling fountain is in use. Water running from the bubbling fountain will be drained through the pipes 25 and 21 and through the trap 15 so that said trap 100 seals the bubbling fountain as well as the

lavatory bowl from foul gases, even when drain pipe 14 is connected to a cess-pool or the like. Water is always available to flow from the tank to the lavatory through pipe 5 20 when valve 19 is open. When it is desired to drain the water tank, valve 18 will be opened while valves 19 and 24 remain closed, and the water will then be discharged from the tank through pipe 21, trap 15 and 10 drain pipe 14.

In practice, it has been found that the combined unit which is a self-contained two-in-one combination, meets all the needs of rural schools and the like and may be supplied at comparatively small cost. It is highly sanitary and affords a supply of cold or cool drinking water as well as a lavatory that supplies water in an adequate but economical manner. Of course, the device illustrated 15 20 in the drawings is capable of modification as to details of construction and arrangement of parts within the spirit and scope of the invention herein disclosed and claimed.

What I claim is:

25 1. A lavatory and bubbling fountain unit comprising a water tank, a lavatory bowl, a bubbling fountain, a drain pipe from the bowl having a water-sealing trap therein, a faucet for said bowl, a water discharge pipe 30 depending from said tank, a normally closed valve in said discharge pipe, a water pipe connecting the faucet of said bowl to said discharge pipe at a point above the valve thereof, a drain pipe connecting the lower 35 end of said discharge pipe to said main drain pipe at a point above its water trap, a valve-equipped water supply pipe leading from said water tank to said bubbling fountain, and a drain pipe from said bubbling fountain 40 connected to said discharge pipe at a point between its normally closed valve.

2. The structure defined in claim 1 in further combination with a framework which supports said tank and lavatory bowl and 45 connects the said parts as a self-contained unit.

3. A combined bubbling fountain and lavatory comprising a tank, lavatory bowl, bubbling fountain, valve-equipped supply and 50 drain pipes connecting said water tank to said bowl and bubbling fountain, and drain pipe connections from said bubbling fountain and bowl, the said parts being supported and combined as a self-contained unit.

55 4. The structure defined in claim 3 in which the drain pipe from said bowl is provided with a water trap and the drain pipe from said bubbling fountain is connected to the drain pipe from said bowl at a point above 60 its water trap.

In testimony whereof I affix my signature.
LEO C. SMITH.
